UNITED STATES PATENT OFFICE.

HARRY L. RANSOM AND JEROME EVERETT EMERSON, OF LOCKPORT, NEW YORK,
ASSIGNORS TO NIAGARA TEXTILE COMPANY, OF LOCKPORT, NEW YORK.

DESIGN FOR A TEXTILE FABRIC OR SIMILAR ARTICLE.

59,034.

Specification for Design. Patented Sept. 13, 1921.

Application filed April 16, 1921. Serial No. 462,041. Term of patent 3½ years.

To all whom it may concern:

Be it known that we, HARRY L. RANSOM and JEROME EVERETT EMERSON, citizens of the United States, residing at Lockport, in the county of Niagara and State of New York, have invented a new, original, and ornamental Design for a Textile Fabric or Similar Articles, of which the following is a specification, reference being had to the

accompanying drawing forming a part thereof.

The figure is a representation of our new design for textile fabric or similar article.

We claim:

The ornamental design for a textile fabric or similar article, as shown.

HARRY L. RANSOM.

JEROME EVERETT EMERSON.
